US0D1041254S

(12) **United States Design Patent** (10) Patent No.: **US D1,041,254 S**
(45) Date of Patent: ** Sep. 10, 2024

(54) **CONTAINER**

(71) Applicant: **Starbucks Corporation**, Seattle, WA (US)

(72) Inventors: **Kathryn Rose Crabb**, Seattle, WA (US); **Mercedita Andrew**, Seattle, WA (US)

(73) Assignee: **Starbucks Corporation**, Seattle, WA (US)

(**) Term: **15 Years**

(21) Appl. No.: **29/891,093**

(22) Filed: **May 1, 2023**

(51) LOC (14) Cl. **07-01**

(52) U.S. Cl.

USPC **D7/511**; D9/452

(58) **Field of Classification Search**

USPC D3/202; D7/300.1, 392.1, 396.2, 507, D7/509, 510, 511, 523, 532, 533, 536, D7/608; D9/435, 449; 220/200, 592.16, 220/592.17

(57) **CLAIM**

The ornamental design for a container, as shown and described.

DESCRIPTION

FIG. 1 is a top perspective view of an example of a container. FIG. 2 is a bottom perspective view of the container of FIG. 1.

FIG. 3 is a front view of the container of FIG. 1.

FIG. 4 is a back view of the container of FIG. 1.

FIG. 5 is a right side view of the container of FIG. 1.

FIG. 6 is a left side view of the container of FIG. 1.

FIG. 7 is a top view of the container of FIG. 1; and,

FIG. 8 is a bottom view of the container of FIG. 1.

The broken lines depict portions of the container that form no part of the claimed design.

1 Claim, 8 Drawing Sheets
